[57] CLAIM

The ornamental design for a tubing slide clamp, substantially as shown and described.

DESCRIPTION

FIG. 1 is a perspective view of a tubing slide clamp showing our new design;

FIG. 2 is a front view thereof, the rear view being identical but a mirror image of the front view;

FIG. 3 is a right side view thereof;

FIG. 4 is a left side view thereof;

FIG. 5 is a top plan view thereof;

FIG. 6 is a bottom plan view thereof;

FIG. 7 is a sectional view thereof taken along line 7—7 in FIG. 1; and

FIG. 8 is a sectional view thereof taken along the line 8—8 in FIG. 1.

FIG. 1

FIG. 2

FIG. 3

FIG. 4

FIG. 7

FIG. 5

FIG. 6

FIG. 8

UNITED STATES PATENT AND TRADEMARK OFFICE
CERTIFICATE OF CORRECTION

PATENT NO. : DES. 279,314

DATED : June 18, 1985

INVENTOR(S) : Masami ISHIDA, et al

It is certified that error appears in the above-identified patent and that said Letters Patent is hereby corrected as shown below:

On the initial page of the printed patent, delete the Foreign
Application Priority Data from the heading thereof.

Signed and Sealed this

Eighth Day of October 1985
